UNITED STATES PATENT OFFICE

168,436

ELECTRIC SHAVER CASE

Louis C. Carissimi, Fairfield, Conn., assignor to Remington Rand Inc., New York, N. Y., a corporation of Delaware

Application February 29, 1952, Serial No. 18,730

Term of patent 7 years

(CL. D58—12)

To all whom it may concern:

Be it known that Louis C. Carissimi, citizen of the United States, residing at Fairfield, State of Connecticut, has invented a new, original, and ornamental Design for an Electric Shaver Case, of which the following is a specification, reference being had to the accompanying drawings, forming a part hereof.

Fig. 1 is a perspective view of the new design for an electric shaver case, shown in open position;

Fig. 2 is a plan view thereof showing the case in closed position;

Fig. 3 is a front elevation thereof; and

Fig. 4 is a side elevation thereof.

The invention claimed is:

The ornamental design for an electric shaver case, as shown.

LOUIS C. CARISSIMI.
